UNITED STATES PATENT OFFICE.

HARVE R. STUART, OF WHEELING, WEST VIRGINIA.

TELEPHONE-RECEIVER.

No. 910,244.

Specification of Letters Patent.

Patented Jan. 19, 1909.

Application filed January 10, 1907. Serial No. 351,578.

To all whom it may concern:

Be it known that I, HARVE R. STUART, a citizen of the United States, residing at Wheeling, in the county of Ohio and State of 5 West Virginia, have invented certain new and useful Improvements in Telephone-receivers, of which the following is a full, clear, and exact description.

Ordinary voice currents are commonly 10 produced by the well known microphone transmitter in which the varying resistance of carbon under pressure is utilized, or by a magnetic induction transmitter in which the fluctuations or undulations are produced 15 by magnetically induced electric currents. In either case the characteristics of the voice currents are substantially the same, that is to say, the current has generally one direction of flow, but the intensity 20 varies continually, and in an apparently irregular way, depending on the character of the sound transmitted. So far as I am aware these voice currents have always been reproduced into sound by the 25 use of an iron diaphragm directly acted upon by an electromagnet in the circuit of the voice currents. I have discovered that this form of instrument does not have the efficiency of conversion that it should. In 30 other words, a great deal of energy is lost in the reproduction.

It is the purpose of the present invention to provide a very much more efficient form of instrument for reproducing the sound 35 from the voice currents, or as it is commonly called, a telephone receiver, and one which approaches the theoretical limit of efficiency which can be possibly attained.

In the drawings: Figure 1 is a diagrammatic view illustrating an application of the principles of the present invention; Fig. 2 is an end view of a practical telephone receiver embodying the invention; Fig. 3 is a vertical sectional view of the same; Fig. 4 is a horizontal section taken generally on the broken line IV-IV of Fig. 2, looking downward; Fig. 5 is a fragmentary perspective view, showing portions of the device.

In order that the principles underlying the 50 present invention may be made clear, I will briefly consider the electrical conditions which are found in the ordinary operation of a telephone circuit. There are two initial sources of energy, one is the usual battery 55 which may be as strong as desired, and the other is the sound wave which initially strikes

the diaphragm of the transmitter. The last factor does not have very much energy, but if all of the energy can be conserved in the transmission the supply of energy will be 60 more than sufficient. In other words, if the energy of transmitted speech were all conserved, the reproduced sound at the receiver would be as loud as or louder than that delivered into the transmitter. This result 65 is not secured in practice even with a microphone transmitter, and the reason is on account of the low efficiency of the ordinary ferrototype diaphragm receiver. The nature of the microphone transmitter is such that 70 it multiplies to a certain extent the energy of the sound wave in transforming it into voice currents. With a receiver, therefore, of ideal efficiency, and a microphone transmitter, the reproduced sound should be very 75 much louder than the original voice. That these conditions are not attained in practice serves to show the very low efficiency attained by the telephone receiver of the ordinary sort. I have found that this low efficiency is largely due to three factors. The first of these is the too great stiffness of the ordinary ferrototype diaphragm employed. The diaphragm should be so light and elastic 80 that all of the energy of its vibrations goes into 85 the air rather than into intermolecular friction or internal heat, as is the case with the ordinary fairly stiff iron diaphragm. The ordinary iron diaphragm transforms only a very small proportion of its energy of vibration 90 into sound waves. The remainder is lost in the work done in moving the molecules of the iron upon one another. The second and still more important cause of the loss of energy 95 is due to the fact that an entirely insufficient quantity of iron is presented to take care of the magnetic flux produced by the voice currents. The receiver is in a sense an electric motor because it produces mechanical movement and delivers power from an electrical 100 current. Certain of the same principles of design should therefore be followed as apply to electric motors. In other words, the iron of the movable and immovable parts should each be sufficiently massive to carry 105 the magnetic flux produced by the windings without saturation. This is not done in the ordinary telephone receiver, because the diaphragm is so light and thin as to imperfectly carry even the fixed flux of the usual permanent magnets. In carrying out the present 110 invention the working parts are designed

strictly in accordance with the principles of ideal efficiency, with provision for sufficiently massive iron parts to carry all the flux due to the impressed magneto motive force. A 5 third, and also very important source of inefficiency in the ordinary telephone receiver, lies in the fact that the forces which are developed by the varying magnetic flux in the iron parts are not transformed into movement of 10 the diaphragm. The diaphragm is quite stiff and is necessarily clamped between fixed rings, and these act of course to powerfully dampen the vibrations of the diaphragm. The condition is analogous to the application 15 of forces to a body which is anchored against any but a very small movement. It is evident that only such small movement will be produced instead of the large movement which would otherwise be induced by the applied forces in case the object were not anchored. These three reasons are the principal, although not all, of the causes of the 20 very low reproductive efficiency which is secured by the ordinary telephone receiver.

25 I will first elucidate the broad principles on which the present invention is based, by the aid of diagrams, and afterwards describe a particular structure in which they are embodied.

30 Referring to Fig. 1, A is a bar of iron, which is fixed in position, and B is another bar of iron which is freely movable toward and from the bar A. In the diagram the bar B is shown as depending from a stem C, 35 flexibly suspended at D. Any arrangement by which the bar B is perfectly free to vibrate will answer the conditions. A magnetic flux is normally impressed to pass between the bars A and B in any suitable way, as, for 40 example, by means of the permanent magnet E, which contacts with the bar A, and is closely adjacent to the bar B along a surface thereof which is parallel to the direction of movement, so that no component of force is 45 produced to move B except the attraction of the pole piece A. The bar B may be balanced against moving toward A in any suitable way, as, for example, by another pole A' and magnet E', similar to A and E respectively, but on the other side of B.

50 G is a magnetic winding or coil which surrounds the bars A and B, and is adapted to superpose its magneto motive force upon that of the permanent magnet E. The essential characteristic is that the bars A and B are sufficiently large to carry the superposed flux of the coil G and the magnet E without becoming saturated. When telephonic or voice currents pass through the 60 winding G, under these circumstances, practically the entire energy thereof is transformed into forces of attraction and repulsion between the bars A and B. This is because the full electrical energy goes to the production of magneto motive force and the full magnetic

force goes into the production of polar attraction between the bars A and B,—in other words, into ordinary mechanical force. The only problem remaining, therefore, is to transform this force into delivered energy at 70 a diaphragm. Now we have seen that the bar B must be sufficiently massive to carry the magnetic flux, and under these circumstances it is so massive that it does not have a wide amplitude of movement under the 75 impressed force by reason of its great inertia. It has all the theoretical energy, however, because what it lacks in amplitude it makes up in mass, and the product or momentum is the theoretical maximum due to the voice 80 currents. The bar B has a movement, therefore, which represents in kinetic energy, practically all the energy of the voice currents. The remaining problem is to transform this energy into operation of a dia- 85 phragm of just sufficient size and amplitude to give the most efficient transmission of the energy to the air. Such a diaphragm I may form of thin mica, supported in a sound box, and I make use of a lever connection between 90 the bar B and this diaphragm, such lever connection having a multiplying effect exactly suited to the requirements. In other words, the multiplying effect is such as to multiply the movement of limited amplitude 95 of the bar B to just the extent which is required to move a diaphragm suited to the most perfect sound reproductive efficiency. By the embodiment of these theoretical principles it is evident that the highest possible reproductive efficiency is secured.

I will now consider the details of the mechanical structure which embodies the foregoing principles. The magnets E, E', of the above described diagrammatic representation are in this case formed by the sheet steel ring sections or segments 1 and 2, each of which has an angular extent of slightly less than a complete circumference. A number of rings are riveted or otherwise 110 secured together to form the magnet, thereby producing a compound magnet of greater strength. To one end of each of the ring sections 1 and 2 is fastened a polar extension 3, which may be of steel or soft iron, and 115 which has an inwardly projecting stud 4, also of soft iron. In practice the inwardly extending studs 4 are formed by screws passed through the polar extensions 3, so as to fall in alinement with one another. 120 These screws correspond to the pole pieces A, A', of the diagrammatic representation above set forth.

5 is a central common pole piece of both magnets having an extension 6 in proximity 125 to the axis joining the poles 4.

7 denotes coils corresponding to the coils G, G', of the above diagrammatic representation, and 8 designates the movable part or armature which vibrates between 130

the pole pieces 4. By this arrangement the armature 8 has exactly the same relation between the poles 4 as the bar B between the poles A, A', of Fig. 1. The armature 5 is also polarized in the same way, that is to say, it has poles of the same character at its two ends, and a single opposite pole at the middle. This polarity is induced by the permanent field magnets which magnetize 10 the two studs 4 of one polarity, and the intermediate extension 6 of the opposite polarity. While this particular arrangement of the magnet poles is not absolutely essential, it has a very great practical advantage. 15 This advantage is that there is no possibility of the flux produced by either coil traversing the armature from one end to the other. If the flux due to the coils or windings traversed the armature from one end to the other, any variations therein would produce changing forces of attraction at both ends of the armature, instead of one end only. If the forces of attraction vary at both ends simultaneously, the effects 20 would neutralize one another, and impair the efficiency. But by having the armature polarized in the manner already described, this effect is absolutely prevented, since the flux of each side is kept entirely separate from the other side, so that there is no neutralization of the forces. In other words, 25 the effects of both windings are added together without any reactions being produced to lessen the efficiency. The armature 30 is supported so as to vibrate freely in a longitudinal direction between the pole pieces 4. The means which I employ for supporting the armature give the same special characteristics in its vibratory movement, and which form an important feature 35 of the invention. Knife edges 11 are supported by a fixed frame. This frame is formed by a standard 13, projecting upward from the base, and having studs 14, which support a box 15. The knife edges 40 11 are fixed to the box 15, and the springs 12 are borne upward by screws 16, which extend through lateral arms 16^a on said box. In this way the armature 8 is held 45 so as to be freely movable toward and from the pole pieces 4, but immovable in any other direction. This arrangement by which the armature 8 is held against the knife edges 11 by the springs 12 not only 50 serves to permit the armature to have a to, and fro movement, but also exerts a certain force to keep the armature in its normal central or mean position. The tension by which the armature is held in 55 its central position may be increased or diminished by adjusting the screws 16. It is important to have a certain tension for this purpose, in order that the armature may acquire the same movements as those 60 of an ordinary sound wave. The sound of an ordinary wave is transmitted by the air, the molecules of which are elastically impelled in a certain relation, and in transmitting a sound wave the molecules are displaced on one side or the other of this 65 position. The armature 8 is therefore correspondingly impelled by the springs 12 into a mean position, and is displaced to one side or the other by the forces of attraction of the magnetic system. As will 70 later appear, a diaphragm is also used which by its own elasticity tends to take a certain normal position. The springs 12 enable the armature to operate properly without relying on the diaphragm to which 75 it is connected in a manner which will be presently set forth.

17 indicates a stem or arm extending from the block 10. This arm is much longer than the stem 9, so that the movements of the 80 armature 8 are multiplied at the extremity of the extension arm 17. The ratio is made a certain value, depending on several factors. The factors which determine this ratio will be later more particularly considered. The 85 upper end of the arm 17 is fixed to diaphragm 18, which is preferably of thin elastic material, such as sheet mica, and which is clamped between rubber rings 19, within the box 15. The diaphragm 18 is made so thin and so 90 elastic as to vibrate very easily and with almost perfect elasticity, so that a minimum amount of the energy of its vibration goes into molecular movement or heat, and a maximum amount of the energy of vibration 95 is delivered to the air in the form of sound. In other words, it is made so that it vibrates with sufficient amplitude to impress sound vibrations on the air with the greatest efficiency, and at the same time is made sufficiently elastic so that it is able to acquire all 100 of the fine vibrations of ordinary speech. Neither of these effects is secured except at extremely low efficiency in an ordinary ferrototype telephone diaphragm, and it is 105 obvious that the diaphragm 18 of the present invention may be made of such material, size and thinness as to attain the very best possible results, unimpeded by any electrical or magnetic considerations. In practice mica clamped between the rubber rings 19, is found to give satisfactory results. The box 15 therefore constitutes a sound box, and has tubular extensions or sound delivery 110 openings 20, to which rubber tubes may be 115 attached, or a sound horn, or any other sound delivering device.

I will now consider the leverage ratio of the extension arm 17 to the stem 9. As has been pointed out in the preliminary part of 120 this specification, the vibrating piece or armature 8 should be made with a quite considerable amount of iron in order that it may carry the entire magnetic flux produced by the various magneto motive forces. This 125 130

condition attained, it is evident that the actual forces impressed on the armature result in certain vibrations thereof which are less in proportion to the size of the armature, 5 but which correspond to a certain energy of vibration in all cases. Now on the other hand, it is found that the very best efficiency of sound transference is obtained from the diaphragm 18 to the air when such 10 diaphragm is made of a certain size, and has a certain amplitude of vibration. It is merely necessary to ascertain this vibration, amplitude and the actual vibration of the armature 8 under the magnetic forces, and 15 then proportion the ratio of the stems 9 and 17 to the respective values. In the drawings the proportion is about the best which I have found in practice. By this arrangement the sound producing diaphragm and 20 the entire electrical and magnetic systems are kept absolutely separate and distinct from one another. Each may be designed and constructed in accordance with the best theoretical principles and the connections, links, levers, or means to transmit the motion from one to the other afterwards applied in the most direct and convenient 25 way.

The magnetic coils 7 may be connected in 30 series or multiple, the multiple arrangement being ordinarily preferable, with any telephone circuit, or circuit in which voice currents are produced. The current fluctuations are transformed into corresponding 35 fluctuations in magneto motive force, and this magneto motive force is transformed into corresponding fluctuations in the flux through the armature with almost perfect efficiency by reason of the large mass of the 40 armature. This varying flux is accompanied by corresponding variations in the force of attraction, so that all of the energy of the voice currents goes into vibration of the armature. This energy is then transferred 45 without substantial loss to the mica diaphragm which is adapted to transform the vibrations into sound waves with the best efficiency. In practice, of course, there is a slight unavoidable loss at each stage due 50 to mechanical friction and other causes, but such slight losses amount only to a very small per cent., so that the apparatus attains practically the perfect condition of delivering in actual sound the entire energy of the 55 voice current fluctuations.

It has already been pointed out that the armature 8 is impelled by the springs 12 elastically into a certain mean position of its movement, and that the diaphragm 18, by 60 its own elasticity normally acquires a certain mean or normal position corresponding to the mean position of the armature and to a state of rest of the system. The forces due to the varying currents in the windings 7 are 65 applied to the armature, and act together to

assist one another to displace the armature to one side or the other of its mean position. The action is entirely symmetrical, the motion corresponding exactly to the molecular movement of the air during a sound wave. 70 The resiliency of the springs 12 influences the movement of the armature to just the extent that the elasticity of the air influences the movement of the molecules. The action is entirely different from that of the ordinary 75 telephone receiver in which the forces are all from one side and by which the diaphragm is constantly arched inward. The result is to obtain perfect purity in the sound delivery. This is attained because the symmetrical and balanced conditions of the constant and the variable forces of the entire system are exactly analogous to those of the air molecules in sound transference. The diaphragm 18 and the armature are designed 80 to vibrate symmetrically on either side of their mean positions, and the forces are adapted to produce such vibrations symmetrically on each side of the mean positions.

The tension of the balancing spring 12, is 90 such as to give the movable system a natural period of vibration higher than that of speech or musical notes which the receiver will be called upon to reproduce.

While I have particularly described this 95 invention as applied to the operation of a telephone receiver, I do not desire to be limited or restricted to this particular use, since it is obvious that the features of the construction are equally applicable to a telephone 100 relay or any other acoustic apparatus where a part is mechanically vibrated by voice currents.

What I claim, is:—

1. In a telephone receiver, a pair of magnets forming parts of separate magnetic circuits, a longitudinally movable armature for each of said circuits, and means movable therewith for transmitting to a distance the movements of the armature corresponding 105 to variations in the flux of said magnetic circuits.

2. In a telephone receiver, a pair of fixed magnets having one pole in common, their other poles being oppositely disposed with 110 respect to each other, and an armature substantially closing the gaps between the poles of said magnets and movable toward and away from the oppositely disposed poles and across the face of the common pole. 120

3. In a telephone receiver, a magnet and an armature therefor movable toward and away from one pole and across the face of the other pole.

4. In a telephone receiver, a diaphragm, 125 an armature having a lever connection therewith whereby its vibration is transmitted to the diaphragm, a pair of magnets each forming separate magnetic circuits in connection with and substantially closed by said arma- 130

ture, whereby the armature is balanced by the combined attraction of said magnets, and means whereby telephonic currents have their energy transformed into magneto motive force and impressed into a varying magnetic flux through said armature whereby the armature vibrates with substantially all the energy of the telephonic currents.

5. In a telephone receiver, a pair of magnets each substantially ring-shaped and having an interrupted portion, a pair of studs projecting inward therefrom and constituting poles, an extension also extending inward and constituting a pole opposite to that 10 of said first mentioned poles, and an armature supported to move toward and from said first mentioned poles and in proximity to said last mentioned pole.

6. In a telephone receiver, a pair of magnets each generally ring-shaped and having an interrupted portion, poles extending inward therefrom, an armature mounted to move in the direction of said poles, and an additional extension from each of said magnets 25 and having opposite polarity to said first mentioned poles and extending into close proximity to an intermediate portion of said armature.

7. In a telephone receiver, a pair of ring-shaped magnets each having an interrupted portion, a sound box between said magnets, an armature supported by said sound box, polar extensions from said magnets extending into proximity to said armature at three 35 points thereof, and a plurality of coils adapted to superpose their magneto motive force on that of said magnets.

8. In a telephone receiver, a plurality of magnets each having an interrupted portion, 40 three polar extensions from said magnets, an armature mounted to move between two of said extensions and in proximity to said third extension, and magnetic coils for superposing a magneto motive force upon that of said magnets.

9. In a telephone receiver, a pair of magnets having two, salient poles and one consequent pole, said salient poles being of like polarity, an armature mounted to move in a 50 direction normal to said salient poles and tangential with respect to said consequent pole and coils adapted to impress their magneto motive force on the flux of said field.

10. In a telephone receiver, an armature, 55 knife edges adapted to support said armature to have a vibratory movement, a pair of springs connected to said armature to hold the same against said knife edges and to resiliently impel it into a mean position of its movement, means for creating a magnetic field to include said armature, and means for superposing a magneto motive force on said field to change the flux thereof.

11. In a telephone receiver, means for creating a magnetic field, an armature therein,

a bar fixed to said armature, a pair of knife edges adapted to support said bar, a pair of resilient springs projecting from said bar, and means for tensioning said springs to press said bar against the knife edges and 70 impel it into a mean position of its movement.

12. In a telephone receiver, means for creating a magnetic field, an armature therein, a sound box, a diaphragm in said sound box, 75 a pair of knife edges projecting from said sound box, a bar supported by said knife edges and rigidly connected to said armature, a pair of springs projecting from said bar, means for impelling said springs toward said sound box whereby said bar is pressed 80 against said knife edges and normally held in a mean position of its movement, and a stem projecting from said bar and attached to said diaphragm.

13. In a telephonic apparatus, a magnet in a circuit adapted to be traversed by voice currents, a doubly polarized armature therefor, an element for amplifying the movements of said armature and means for propagating the effect of such amplification. 90

14. In a telephone receiver, a magnet, an armature therefor movable toward and away from one pole and across the face of the other pole and a connection for transmitting to a distance the movements of the armature. 95

15. In a telephone receiver, a pair of magnets and an armature movable toward and away from one pole of each magnet and 100 across the face of the other pole thereof.

16. In a telephone receiver, a pair of magnets, an armature movable toward and away from one pole of each magnet and across the 105 face of the other pole thereof and resilient means for normally holding said armature member in definite relation to said magnets.

17. In a telephone receiver, a pair of magnets and an armature adapted to be influenced by voice currents, said armature being 110 elongated and longitudinally movable, and said magnets being capable of moving said armature in opposite directions away from its normal or mean position, an element having an amplified movement with respect to said armature, means for propagating the effect of such amplification, and resilient means separate and distinct from said propagating means and operating to perform the function of directing the armature from 115 either of its extreme positions into or toward its normal or mean position.

18. In a telephone receiver, a magnet and armature adapted to be influenced by the voice currents, said armature being elongated in the direction of the flux of the magnetic circuit and longitudinally movable, an element having an amplified movement with respect to said armature, and means for propagating the effect of such amplification. 125 130

6

19. In a telephone receiver, a magnet adapted to be influenced by the voice currents, a diaphragm, an armature elongated in the direction of the flux of the magnetic circuit and longitudinally movable, and a multiplying connection between the armature and diaphragm.

20. In a telephone receiver, a pair of magnets forming parts of separate magnetic circuits, an elongated longitudinally movable member forming an armature for each of said circuits, said armature being polarized at each end with similar poles, an element having an amplified movement with respect to said armature, and means for propagating the effect of such amplification.

21. In a telephone receiver, a magnet, a coil through which the voice currents pass and adapted to vary the magnetic flux of said

magnet, an elongated longitudinally movable armature extending into the space surrounded by the coil, an element having an amplified movement with respect to said armature, and means for propagating the effect of such amplification.

25

22. In a telephone receiver, a pair of ring-shaped magnets each having an interrupted portion, a sound box including a diaphragm situated in the space between said magnets, an armature, and a lever connection between said armature and said diaphragm.

In witness whereof, I subscribe my signature, in the presence of two witnesses.
